INVENTOR

UNITED STATES PATENT OFFICE.

RICHARD W. JONES, OF SYRACUSE, NEW YORK.

DESIGN FOR A HAME-TERRET.

SPECIFICATION forming part of Design No. 12,513, dated October 4, 1881.

Application filed August 25, 1881. Term of patent 7 years.

To all whom it may concern:

Be it known that I, RICHARD W. JONES, a citizen of the United States, residing at Syracuse, in the county of Onondaga and State of New York, have invented and produced a new and original Design for Hame-Terrets, of which the following is a specification, reference being had to the accompanying drawing, which represents a perspective view of my newly-de-
10 signed hame-terret.

Heretofore hame-terrets have been made with the ring-brace coming down to the staff and terminating above the lower staple-groove in the staff, while the lower end of the staff
15 below the lower staple-groove was made to terminate with a knob of acorn or other shape.

The leading features of my design consist in extending the ring-brace downward with an ogee or other curve and rounding downward
20 until it meets the upturned extremity of the staff below the lower staple-groove, substantially as shown in the drawing.

A is the ring, which may be circular, oval, or

semi-oval in form, as desired. B is the staff. C is the ring-brace. D is the upper staple-groove, and E is the lower staple-groove. The staple-grooves D and E are generally located as shown in the drawings. The ring A, staff B, and brace C are made or cast all in one piece. The staples which hold the terret in place upon the hame fit in the grooves D and E.

30

I claim—

The design for a hame-terret herein shown and described, the same consisting of the ring A, staff B, provided with staple-grooves D and E, and the ring-brace extended downward until it meets the upturned lower extremity of the staff B, substantially as shown and described.
35

In witness whereof I have hereunto set my hand this 22d day of March, 1881.

RICHARD W. JONES.
